United States Patent Office.

WILLIAM MAROT MARSHALL, OF PHILADELPHIA, PENNSYLVANIA.

Design No. 3,012, dated May 5, 1868.

DESIGN FOR A MEDALLION-HEAD OF GENERAL GRANT.

The Schedule referred to in these Letters Patent and making part of the same.

Be it known that I, WILLIAM MAROT MARSHALL, of the city of Philadelphia, and State of Pennsylvania, have originated and designed a new Medallion in basso-relievo, of which the following is a full, clear, and exact description, reference being had to the accompanying specimen, and making part of the specification.

The nature of the design is a medallion in plaster, or other material, in basso-relievo, being a representation of the head and neck of General Grant, said basso-relievo to be made of plaster or gilders' composition, or other material, and placed on a ground-work of plaster, or velvet, or velvet paper, or on silvered glass, or glass colored with paint or other material. Said basso-relievo may also be bronzed, lacquered, gilt, or silvered, or otherwise finished and framed, or otherwise arranged for display.

What I claim as my invention, and desire to secure by Letters Patent, is—

The design for a medallion in basso-relievo, as herein set forth and shown.

Philadelphia, January 30, 1868.

WILLIAM MAROT MARSHALL.
